UNITED STATES PATENT OFFICE.

CARL WESTROM, OF MADDOCK, NORTH DAKOTA.

TOOL.

949,030.

Specification of Letters Patent. Patented Feb. 15, 1910.

Application filed May 15, 1909. Serial No. 496,176.

To all whom it may concern:

Be it known that I, CARL WESTROM, a citizen of the United States, residing at Maddock, in the county of Benson and State of 5 North Dakota, have invented a new and useful Tool, of which the following is a specification.

My invention relates to combination wrenches and has for its object to provide a 10 device of this kind which can be used either as an adjustable wrench or a pair of nippers.

Another object is to provide a device that is easily adjusted and the movable jaw locked in position when adjusted without 15 the use of the threaded shank and traveling nut so common in the usual style of combination wrenches.

Another object is to provide a device of 20 this character wherein the grip of the operator's hand on the handle suffices to lock the parts in position, whereby the tool is ready for use immediately on being placed into operative position.

With these and other objects in view, 25 which will be described in the following specification, my invention embraces the structure illustrated in the accompanying drawing, wherein:—

Figure 1 is a side elevation of the wrench. 30 Fig. 2 is a similar view showing parts in longitudinal section.

In a more detailed description of my invention, in which like characters of reference designate similar parts in the views shown, 35 (1) is a fixed jaw of the wrench, having a sleeve (2) terminating in the handle (3), integrally formed therewith. This jaw is of double form, that is it has two working faces (4) and (5), the working face (4) being transversely grooved and terminating 40 in the sharp edge (6), to adapt the same for cutting wire or other small rounded bodies. The face (5) is flat and is adapted for use 45 in tightening nuts or other bodies having square surfaces. The sleeve (2) has formed therein a cavity (7) in axial alinement with the sleeve, extending downward from the working face (5). One side of the sleeve is beveled, as shown at (8), and in this beveled 50 portion is formed a rectangular opening, communicating with the cavity (7). In the sides of the sleeve are also formed longitudinally arranged slots (9), communicating with the cavity (7). These slots are widened 55 on one side adjacent to their lower ends to form sight holes (10). The sliding jaw

(11) has the working faces (12) and (13) arranged correspondingly, and adapted to work in conjunction with the working faces of the fixed jaw (1) and sleeve (2). 60 Formed integrally with the sliding jaw, and projecting downward therefrom is the shank (14), adapted to slidely fit the cavity (7), and of such length as to enable the jaws to meet when the lower end of the shank rests 65 on the bottom of the cavity formed in the sleeve (2). This shank has a longitudinal cavity 15 formed therein adapted to communicate with the slots (9). One side of the cavity (15) is provided with a series of 70 ratchet teeth, (16), the purpose of which will hereinafter be explained. A lug (17) is formed on the rear side of the sleeve (2) and pivoted therein at (18) is the lever or handle (19) which is also provided with a 75 lug (20), disposed adjacent the pivoted end of said handle. Pivoted secured at (21) in said lug 20 is a locking frame, consisting of two side bars (22), and the locking rib (23) which engages the ratchet teeth 80 (16) in the cavity (15) when the jaws are locked to fit a certain sized nut or piece of wire. This locking rib is essentially triangular in contour, preferably formed integrally with the side bars (22) and of a 85 length sufficient to allow said side bars to slidely fit the sleeve (2) in order that when the handles are spread apart the side bars (22) will slide easily upward over the sides of the sleeve, whereby the locking rib (23) 90 is raised and disconnected from the ratchet teeth. The handles (3) and (19) are bent outward, the opposed faces forming the sides of an acute angle, wherein may be seated the ends of the spring (24), the purpose of 95 which is to keep the handles separated when in normal position so that the locking rib (23) will not engage the teeth.

The operation of the wrench is as follows:—When it is desired to adjust the 100 wrench to any sized nut, the sliding jaw is pulled out so that the working faces engage the sides of the nut when by simply tightening the grip on the handles, the handle or lever (19) is moved inward. This motion 105 lowers the pivoted locking frame and causes the locking rib to engage the ratchet teeth (16). In this condition the wrench is firmly fixed at its proper adjustment and cannot be changed until the handles are 110 spread apart.

The handles when in normal position are

kept spread apart by the spring (24) thereby causing the locking rib to disengage from the ratchet teeth whenever the grip is loosened. In this way the wrench 5 will alternately grip and release the nut as the grip is tightened or relaxed so that as soon as a new grip is desired on the nut the operator has only to relax his grip and the locking rib is released when the jaws can 10 be slid back over the nut until the handle and lever are again compressed when the jaws grip the nut again. Thus the wrench need not be entirely disengaged from the nut at each new grip as in the usual form of 15 wrenches.

When it is desired to use the device as a pair of nippers it is only necessary to adjust the cutting jaws to the surface to be cut and tighten the grip on the handles 20 when the cutting faces will be drawn together.

From the foregoing description, taken in connection with the accompanying drawings, the construction and operation of the 25 invention will be readily understood without requiring a more extended explanation, it being understood that various changes in the form, proportion and minor details of the construction may be made without departing from the principle or sacrificing any 30 of the advantages of the invention.

Having thus described my invention, what I claim is:—

1. A device of the kind described, comprising a fixed jaw, terminating in a handle, 25 said jaw having a longitudinal cavity, and lateral slots communicating with said cavity, a sliding jaw adapted to work in con-

junction with said fixed jaw, and having an apertured shank provided with a longitudinal series of teeth on one side of the aperture in the shank, a handle pivoted on said fixed jaw, and a locking member pivotally secured to said handle, said locking member having spaced bearing portions terminating in a tooth engaging rib, whereby to lock the parts in position. 40 45

2. A device of the kind described, comprising a fixed jaw, having a sharp and a flat working face, said fixed jaw having a cavity opening downward from the working faces and lateral slots communicating with said cavity, a sliding jaw having a sharp and flat working face adapted to work in conjunction with the corresponding working 50 faces of said fixed jaw, said sliding jaw having a shank adapted to slidably fit said fixed jaw, and having a series of ratchet teeth formed in said shank, a handle pivoted to said fixed jaw, a locking frame pivotally secured to said handle, said locking frame having bearing portions, adapted to slidably fit the fixed jaw, and terminating in a transversely disposed locking rib adapted to engage the teeth on the shank of the sliding jaw whereby 55 to lock the parts in position, and a spring seated between the handles of said fixed and sliding jaws. 60

In testimony that I claim the foregoing as my own, I have hereto affixed my signature 70 in the presence of two witnesses.

CARL WESTROM.
